UNITED STATES PATENT OFFICE.

WINFIELD S. HUSON, OF TAUNTON MASSACHUSETTS, ASSIGNOR TO THE CAMPBELL PRINTING PRESS & M'F'G CO., OF NEW YORK, N. Y., A CORPORATION OF NEW YORK.

SIDE GUIDE FOR PRINTING-PRESSES.

No. 878,957.

Specification of Letters Patent.

Patented Feb. 11, 1908.

Application filed April 28, 1892, Serial No. 431,023. Renewed July 5, 1907. Serial No. 382,349.

To all whom it may concern:

Be it known that I, WINFIELD S. HUSON, a citizen of the United States, residing at Taunton, in the county of Bristol and State of Massachusetts, have invented a new and useful Improvement in Side Guides for Printing-Presses, of which the following is a specification.

The aim of this invention is to provide a new and improved side-guide for the feed-boards of printing presses, folding machines or other devices, which shall be capable of easy and accurate adjustment, which shall be so arranged that the edges of the sheets will not catch, and so that the guide will not mar the surface of the feed-board.

To these ends, the invention consists of the devices described and claimed in this specification, and illustrated in the accompanying drawing, in which,

Figure 1 is an end view of my improved guide, Fig. 2 is a side view, Fig. 3 is a vertical section, Fig. 4 is a plan view of a feed-board with my guide applied thereto, and also with 25 stops for my device arranged thereon, Fig. 5 is a section of one of the stops, showing the manner in which it is secured to the feed-board, and Fig. 6 is a view showing my guide arranged with a double gage.

Referring to the drawing and in detail, 1 represents a feed-board. This feed-board has a transverse slot 2 cut in the face of the same, the forward or lower edge of which is beveled outwardly, as shown. Fastened to 35 the board by screws 4 is a metal strip 3, which extends partially over the slot 2, and the top of the strip is arranged flush with the surface of the board. A block 5 has a tongue 90 adapted to fit into the slot 2, as shown in 40 Fig. 3, and also a groove into which the strip 3 may enter so that the block 5 may be slid on to the feed-board transversely. A screw 60 having a head 6 is tapped into the block 5, so that the end of the screw bears on the 45 top of the strip 3. By this means, the block 5 can be secured in any desired transverse position. A gage 9 is arranged to bear on top of the block, as shown, the same having a slot 90^x, through which the screw 60 passes. 50 This gage has extending prongs 10, as shown, which are so arranged as to fit into the slot 2. A nut 7 is threaded on the screw 60, and by this means the gage may be clamped to the

block. If desired, a washer 29 may be arranged between the nut 7 and the block 5. 55 A lug 50 is formed on the block 5, and tapped into this lug is a screw 80 which has a head 8, which head 8 fits into a notch cut in the gage 9, as shown in Fig. 4. By means of this screw, the gage 9 may be nicely adjusted 60 transversely after the block 5 has been secured in position, and when the gage 9 has been brought to the proper position, the same may be secured by screwing the nut 7 down on the same. 65

Suitable stops as 11 may be fitted on to the strip 3, as shown in Fig. 5, and each stop is provided with a clamping screw 12, by which the same may be held in position.

The way my device is used is as follows:— 70 If it is desired merely to use my device as a side guide for sheets, the block 5 is secured in position, and the gage 9 is adjusted so that the sheets will be accurately guided into the machine. The gage 9 has both ends 75 extending down into the slot 2, as shown in Fig. 1, so that the same may be used at either side of the board, as desired. As the lower edge of the recess 2 is inclined outwardly, as shown, the sheets will pass over the same 80 without catching, and as the ends of the gage fit into the slot 2, the edges of the sheets cannot get under the same. The projections 10 also prevent sheets from catching under the gage, in case the corners of the sheet should 85 strike against my device.

My device may be also used when it is desired to perfect sheets. When this is desired, the guide is set, as before described, and one of the stops 11 is brought up against 90 the gage after the same has been adjusted, and the stop is secured in position, as shown in full lines in Fig. 4. Now it is generally desired to perfect some of the sheets before the whole lot is finished so as to see exactly how 95 the printing is coming out. When this is desired, the screw 60 is released, and the device moved to the opposite side of the board, the sheets being turned around so that the same edge of the same will come 100 against the gage 9, and by means of a second stop 11, the proper position of the gage can be easily determined, and kept by securing this stop 11 in position against the adjusted position of the gage 9. After the two stops 105 11 have been set in this manner, the device

can be shifted from one side of the board to the other as often as desired, as the stops 11 being secured to the plate 3, determine the exact position of the gage without further 5 adjustment.

With former arrangements, if the feed board should warp, sheets will be very apt to get under the side guide, but with my improved device, the guide is always in working 10 condition, for even if the board does warp, the strip 3 will conform thereto, and sheets can never get under the guide.

Sometimes two sheets are fed to the press to a center gage from opposite sides of the 15 feed-board. In this case, it is desirable to have the gages adjustable independently on each side, and Fig. 6 shows a device which is used to accomplish this result. In this case, the block 5 is provided with two gages 9, 20 each of which has only one downward extension, and each gage may be independently adjusted by a screw 18 similar to the screw 80 of the previous device, and both gages may be secured in place by the nut 7. 25 As these gages are independently adjustable, they may be set so as to properly guide both sheets.

The details and arrangements herein shown and described may be greatly varied 30 by a skilled mechanic without departing from the scope of my invention, as expressed in the claims.

Having thus fully described my invention, what I claim and desire to secure by Letters- 35 Patent is:—

1. The combination of a feed-board, a transverse slot cut therein, the lower edge of 40 said slot being beveled or cut away outwardly to allow the free passage of sheets, and an adjustable side-guide fitting within and guided by said slot.

2. The combination of a feed-board, a transverse slot cut therein, the lower edge of 45 said slot being beveled or cut away outwardly to allow for the free passage of sheets, a metallic strip secured to said board, and extending partially over said slot, a side-guide mounted to slide on the projecting part of said strip, and means whereby said side- 50 guide can be clamped on to said strip in any adjusted position.

3. The combination of a feed-board having a transverse slot extending across the same, the lower edge of said slot being beveled or inclined outwardly, a metallic strip 55 extending over the upper edge of the slot, an adjustable side-guide fitted on said metallic strip, and means whereby said side-guide can be clamped transversely at any point on 60 the feed-board.

4. The combination of a feed-board having a transverse slot, the lower edge of which is inclined outwardly, a metallic strip fitting over the upper edge of said slot, an adjustable 65 block mounted on said strip, a gage car-

ried by said block, and means for adjusting said gage on said block.

5. The combination of a slotted feed-board, a metallic strip projecting over the slot, an adjustable block mounted on said strip, a clamping-screw for securing the block in its adjusted position, a gage having a slot for receiving the clamping-screw, and a nut threaded on to the clamping-screw for securing the gage in its adjusted position. 75

6. The combination of a feed-board, an adjustable block carried thereby, a clamping-screw for securing the block in its adjusted position, an independently adjustable gage mounted on said block, a transverse adjusting screw controlling the position of said gage, and a clamping nut mounted on the clamping-screw adapted to secure the gage in its adjusted position. 80

7. The combination of a feed-board having 85 a transverse slot, the lower edge of the slot being cut away or beveled, a securing strip extending over said slot, an adjustable block mounted on said strip, a clamping screw for securing the block in its adjusted position, an independently arranged slotted gage fitted 90 to said block, means for adjusting the gage, and means for clamping it in its adjusted position.

8. The combination of a feed-board, a 95 transverse slot cut therein, a metallic strip secured to said feed-board and extending over said slot, a block having a tongue entering said slot, and a groove into whith the strip may fit, a clamping screw tapped into 100 said block and arranged to bear on said strip, and a side gage carried by said block.

9. The combination of a feed-board, a transverse slot extending across the same, the lower edge of said slot being beveled outwardly, a block fitted to slide in said groove, 105 means for clamping said block in any adjusted transverse position, and a two-armed gage secured to said block whereby the device may be used as a feed gage at either side 110 of the board.

10. The combination of a feed-board, a transverse slot cut across the same, the lower edge of said slot being beveled outwardly, a block fitted to slide in said slot, 115 means for clamping said block in any adjusted transverse position, a two-armed gage fitted to said block, and a plurality of stops whereby the device may be shifted and quickly set to act as a feed gage at either side 120 of the board.

11. The combination of a feed-board having a transverse slot, the lower edge of which is beveled or cut away, a securing strip extending over the edge of said slot, an adjustable block mounted on said strip, a two-armed gage fitted to said block, a stop fitted on said strip, and means whereby said stop 125 can be adjustably secured thereon.

12. The combination of a feed-board hav-

ing a transverse slot therein, the lower edge of said slot being beveled or cut away to allow the free passage of sheets, an adjustable block mounted in said slot, a clamping screw for securing the block in its adjusted position, an independently adjustable gage mounted on said block, a transverse adjusting screw controlling the position of said gage, and a clamping nut mounted on the

clamping screw adapted to secure the gage in its adjusted position.

In testimony whereof I have hereunto set my hand, in the presence of two subscribing witnesses.
